Samuel Hoffman

BY his ATTORNEY

Andrew T. Lee Jr.

UNITED STATES PATENT OFFICE

SAMUEL HOFFMAN, OF SOUTH ORANGE, NEW JERSEY, ASSIGNOR TO J. CHEIN & COMPANY, OF HARRISON, NEW JERSEY, A CORPORATION OF NEW YORK

SAIL BOAT

Application filed July 27, 1931. Serial No. 553,312.

My invention relates to toy boats and method of constructing the same.

An object of my invention is to provide a simple and instructive toy; a further object of my invention is to provide a water-tight toy boat; a further object of my invention is to provide a simple and convenient means for constructing a toy boat having a water tight hull; a further object of my invention is to provide water tight means for attaching the keel or other part to a boat to the keel; a further object of my invention is to provide means for making water tight the aperture for the rudder post in a toy boat; a further object of my invention is to provide means for holding the rudder in position.

I accomplish the above objects by the toy boat illustrated in the accompanying drawing, in which

Figure 1 is a view of a boat embodying my invention,

Figure 2 is a longitudinal section of the partly shaped blank for the hull,

Figure 3 is a section of the hull and keel, and

Figure 4 is a detail of the rudder post and sealing means on the line 4-4 in Figure 1.

Similar characters of reference refer to similar parts throughout the several views.

The invention relates particularly to the hull of a toy boat constructed of sheet iron, tin plate or other like sheet material.

In constructing toy boats of this type difficulty has been heretofore experienced in providing means for securely attaching the keel or other part of the hull without leaving seams which are likely to open with use and destroy the water tight character of the hull.

The hull of a toy boat embodying my invention may be of any desired contour.

I provide in the hull 1 of the boat, a longitudinal integral groove 2 by bending the sheet material of which the hull is constructed without opening or breaking the material.

The keel 3 or other part to be attached to the hull 1 is provided with a bead 4 which

may be conveniently done by folding over the material of which it is constructed.

I prefer to use a keel of sheet material to which is secured a suitable weight portion 5, and to fold over the upper marginal edge section of the keel to form the above mentioned bead 4 integral therewith.

In constructing the hull, I prefer to first stamp out the blank with a comparatively wide groove 2 as shown in Fig. 2 and then to place therein the bead 4 on the upper edge of the keel and press in the sides of the groove thus forming converging lips to frictionally engage the said bead 4, thus firmly gripping the bead and holding the keel in position.

It is also desirable to seal the aperture 6 in the hull 1 which carries the rudder post 7.

For this purpose, I provide on the rudder post 7 a rubber washer or gasket 8 having a neck portion 8¹ which fits in the rudder post 7 aperture and seals the same against the admission of water to the hull. Below the gasket 8 I provide on the post 7 a coiled spring 9 which is seated on a lug 10 and bears against the under side of the rubber gasket 8 and holds it in position. As the coiled spring 9 presses against the lug 10 on the rudder post 7, it serves to frictionally hold the rudder against lateral movement so that the rudder may be set and held in any desired position for steering the boat, and the gasket or washer 8 serves to protect the hull from being scratched by the movement of the upper end of the spring 9.

Having thus described my invention, what I claim is:

1. In a toy boat constructed of sheet material, a groove in the said material formed by bending the same, a keel, a bead on the upper marginal edge of the keel inserted in the said groove and secured therein by frictional contact with the sides of the groove.

2. In a toy boat formed of sheet material, a groove therein formed by bending the said material, the said groove having converging lips, a keel seated in said groove and a head on said keel engaged by the said converging lips whereby the keel is secured to the boat.

3. In a toy boat, the combination of a hull 100 a keel secured to the hull, a rudder post in the

hull, an aperture in the hull to receive the rudder post, a gasket upon the rudder post positioned exteriorly of the hull and adapted to seal the said aperture, and spring means for holding the gasket in position.

5. In a toy boat, the combination of a hull, an aperture in the hull adapted to receive a

rudder post, a rudder post seated in said aperture, a gasket on the said rudder post and arranged exteriorly of the hull, a lug on the rudder post, spring means between the said gasket and the said lug adapted to retard by 70 friction the movement of the rudder post.

SAMUEL HOFFMAN.
